CLAIM

The ornamental design for a remote controller for household appliance, as shown and described.

DESCRIPTION

FIG. 1 is a perspective view of the front, right and top sides of a remote controller for household appliance showing our new design;

FIG. 2 is a front view thereof;

FIG. 3 is a rear view thereof;

FIG. 4 is a left side view thereof;

FIG. 5 is a right side view thereof;

(Continued)

FIG. 6 is a top view thereof; and,
FIG. 7 is a bottom view thereof.

1 Claim, 5 Drawing Sheets
